(57) **CLAIM**

The ornamental design for a peripheral for a portable media device, as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by any one of the patent disclosure as it appears in the Patent and Trademark Office patent files or records, but otherwise reserves all copyright and trade dress rights whatsoever.

The nature and intended use is for use as a handheld, self contained, portable, and fashionable, amplifier sound system designed for a portable music device.

FIG. 1 is a perspective view of a peripheral.

FIG. 2 is a front elevational view of the peripheral.

FIG. 3 is a left side elevational view of the peripheral.

FIG. 4 is a right side elevational view of the peripheral.

FIG. 5 is a rear elevational view of the peripheral.

FIG. 6 is a top plan view of the peripheral; and,

FIG. 7 is a bottom plan view of the peripheral.

The dashed broken lines shown on the surface and body of the claimed design represent top stitching.
